UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS SONS & MAXIM, LIMITED, OF WESTMINSTER, ENGLAND.

FIELD-GUN CARRIAGE.

No. 797,502.

Specification of Letters Patent.

Patented Aug. 15, 1905.

Application filed March 14, 1904. Serial No. 198,169.

To all whom it may concern:

Be it known that we, ARTHUR TREVOR DAWSON, lieutenant of the Royal Navy, director and superintendent of ordnance works, and GEORGE THOMAS BUCKHAM, engineer, subjects of the King of Great Britain, both residing at Vickers Sons & Maxim, Limited, 32 Victoria street, Westminster, in the county of London, England, have invented certain new and useful Improvements Relating to Field-Gun Carriages, of which the following is a specification.

Our invention relates to field-gun carriages, and has for its chief object to so construct the same that when traveling the weight on the wheel-axle of the carriage and the wheel-axle of the limber, to which the carriage is connected for traveling, can be equalized, thereby reducing the wear and tear on the wheels. To effect this object, the cradle in which the gun recoils is trunnioned in the top carriage, which is made capable of sliding longitudinally on the trail by suitable mechanism, so that the gun, the cradle, and the top carriage may together be shifted backwardly to a sufficient extent to equalize the loads on the carriage and limber-wheels for traveling as aforesaid. We may also arrange to have the gun (when in the traveling position) secured to the trail by means of a quickly-detachable securing-band embracing the chase of the gun, said band being preferably arranged to be held by the same locking-bolts as are used to secure the top carriage when the gun is in the firing position.

In order that our said invention may be clearly understood and readily carried into effect, we will describe the same more fully with reference to the accompanying drawings, in which—

Figure 1 is a side elevation, and Fig. 2 a plan, of a field-gun carriage constructed in accordance with our invention, the gun and carriage being represented in the firing position. Fig. 3 is a side elevation of the said gun and carriage in the traveling position and connected with the limber. Figs. 4 and 5 are cross-sections taken, respectively, on the lines 1 1 and 2 2 of Fig. 1; and Figs. 6 and 7 are cross-sections taken, respectively, on the lines 3 3 and 4 4 of Fig. 3.

In Figs. 1 and 3 one of the road-wheels of

the carriage and the limber has in each case been removed for sake of clearness.

A is the gun, which is adapted to recoil in the cradle B in the ordinary manner.

C is the top carriage in which the cradle is trunnioned.

D is the trail, the rear end of which is provided with a spade to enter the ground, as usual, when the gun is in firing position, and with an eye adapted to be hooked to the limber E when the gun is in traveling position. The forward end of the trail is supported by the wheel-axle D', on the ends of which are mounted the wheels D² of the gun-carriage, as heretofore. The said wheel-axle is curved to the arc of a circle struck from the spade and is provided with teeth gearing with a worm which receives its motion from a hand-wheel D³, as is well understood, to cause the trail, together with the gun, to slide laterally on the wheel-axle about the spade as a center.

D⁴ is the elevating hand-wheel, which imparts motion to the rack D⁵ to elevate the gun in the well-known manner.

The top carriage C comprises two side pieces, each having a trunnion-bearing, and these two side pieces are connected together by a suitable transom or transverse bar c, Figs. 4 and 5. The under part of the top carriage rests on the trail which is formed with guideways d d for allowing the said carriage to be slid longitudinally thereon, said guideways being preferably arranged to be horizontal when the trail is "limbered up," so as to make the labor of moving the gun and top carriage as light as possible. These guideways are preferably undercut or otherwise suitably made for enabling the guides or clip portions c' of the top carriage to engage therewith, and thus also secure the latter to the trail. A rack d⁶ is fixed to the trail, and a pinion d⁷ (or other suitable gear) is mounted on the top carriage, the latter being actuated by the handle D⁸, Fig. 2, which is also mounted on the top carriage. This arrangement enables the gun and top carriage to be the more easily moved when the position of the carriage prevents the guideways of the trail from being horizontal. Rollers c² may be interposed between the top carriage and the trail, so that the top carriage and gun may be the more easily moved when being

shifted backward or forward. The said top carriage is furnished with eyes or lugs c^3 at its forward part, and the trail is formed with holes at d^1 d^2 , with which the said eyes c^3 will coincide when the top carriage is shifted into its extreme forward or rearward position. The said top carriage can then be locked in its shifted position by means of bolts d^4 or other suitable locking devices engaging with the holes d^1 or d^2 and the eyes c^3 . To prevent the said bolts from becoming unintentionally detached, they may have flanged heads formed with notches, which must be caused to register with fixed projections d^5 by angularly displacing said bolts to permit them to be removed. Chains d^6 connect the bolts with the trail, so as to prevent their becoming removed from the trail and lost. The aforesaid clip portions c' , the locking-bolts d^4 , and the eyes c^3 are all made of such strength as to insure a satisfactory transmission of the stresses of firing from the top carriage to the trail. The rear ends of the guideways are provided with stop-pieces d^7 for limiting the extent to which the top carriage can be shifted and also to insure that the eyes thereon will arrive opposite the holes in the trail when said top carriage is fully shifted in the rearward direction.

When it is desired to move the top carriage relatively to the trail, the elevating-rack D^5 is disconnected from the cradle and detached. Then by actuating the handle D^8 in one direction, Fig. 2, the top carriage can be caused to travel on the trail into its rearward position, (represented in Fig. 3,) which is the position for traveling, and by actuating said handle in the opposite direction the top carriage can be caused to travel into its forward position, (represented in Fig. 1,) which is the position for firing.

Fig. 3 and 7, is the detachable band, which can be arranged around the chase of the gun when it is in traveling position, and thereby assist in securing the gun to the trail. The said band is adapted to be connected with the trail by the locking-bolts d^4 , that are used to secure the top carriage C in place when the gun is in its firing position. In the example illustrated at Fig. 7 the said band is made in two parts, of which the part a' has screw-threaded ends that pass through openings in the other part and receive nuts a^2 for causing the band to firmly grip the chase of the gun. At the same time the said nuts a^2 and bolts d^4 provide a ready means for enabling the band to be quickly detached when so desired.

What we claim, and desire to secure by Letters Patent of the United States, is—

1. In a field-gun carriage, the combination with the gun, of a cradle in which said gun recoils, a top carriage in which the cradle is trunnioned, guides on said top carriage engaging with longitudinal guideways in the trail, means for shifting said top carriage longitudinally on the trail, and means

for temporarily retaining it in its shifted positions, for the purpose specified.

2. In a field-gun carriage, the combination with the gun, of a cradle in which said gun recoils, a top carriage in which the cradle is trunnioned, guides on said top carriage engaging with longitudinal guideways in the trail, means for shifting said top carriage along said guideways, and means for locking said top carriage in its shifted positions for the purpose specified.

3. In a field-gun carriage, the combination with the gun, of a cradle in which said gun recoils, a top carriage in which the cradle is trunnioned, guides on the said top carriage engaging with longitudinal undercut guideways in the trail, means for shifting said top carriage along said guideways, and means for locking said top carriage in its shifted positions for the purpose specified.

4. In a field-gun carriage, the combination with the gun, of a cradle in which said gun recoils, a top carriage in which the cradle is trunnioned, guides on the said top carriage engaging with longitudinal undercut guideways in the trail, antifriction-rollers interposed between the top carriage and the trail, means for shifting said top carriage along said guideways and means for locking said top carriage in its shifted positions for the purpose specified.

5. In a field-gun carriage, the combination with the gun, of a cradle in which said gun recoils, a top carriage in which the cradle is trunnioned, guides on said top carriage engaging with guideways in the trail, means for shifting said top carriage along said guideways, means for limiting the extent of movement of said top carriage along the guideways, and means for locking said top carriage in its shifted positions for the purpose specified.

6. In a field-gun carriage, the combination with the gun, of a cradle in which said gun recoils, a top carriage in which the cradle is trunnioned, guides on said top carriage engaging with guideways in the trail, means for shifting the top carriage along the guideways, an eye on said top carriage, and locking-bolts coöperating with said eye when the top carriage reaches either of its extreme positions on the trail, for the purpose specified.

7. In a field-gun carriage, the combination with the gun, of a cradle in which said gun recoils, a top carriage in which the cradle is trunnioned, guides on said top carriage engaging with guideways in the trail, toothed gearing actuated by a handle on the top carriage for shifting the latter along said guideways, and means for locking said top carriage in its shifted positions, for the purpose specified.

8. In a field-gun carriage, the combination with the gun, of a cradle in which the gun

recoils, a top carriage in which the cradle is trunnioned, means for shifting said top carriage longitudinally on the trail, means for temporarily retaining it in its shifted position, and readily-detachable means for connecting the chase of the gun with the trail for the purpose specified.

9. In a field-gun carriage the combination with the gun, of a cradle in which the gun recoils, a top carriage in which the cradle is trunnioned, means for shifting said top carriage longitudinally on the trail, an adjustable band embracing the chase of the gun, and means for enabling said band to be detachably connected with the trail by the same locking-bolts as those used for locking the top carriage in its firing position, for the purpose specified.

10. In a field-gun carriage, the combination with the gun, of a cradle in which the gun

recoils, a top carriage in which the cradle is trunnioned, means for shifting said top carriage longitudinally on the trail, a band embracing the upper part of the chase of the gun, means for detachably connecting said band at its ends to the trail, a band embracing the under part of the chase of the gun and having screw-threaded ends passing through apertures in the first-mentioned band, and screw-nuts engaging with said ends substantially as and for the purpose specified.

In testimony whereof we have hereunto set our hands, in presence of two subscribing witnesses, this 29th day of February, 1904.

ARTHUR TREVOR DAWSON.
GEORGE THOMAS BUCKHAM.
